WATERCRAFT

Alexander Herman, Berlin, Germany

Application June 3, 1936, Serial No. 83,314
In Germany June 4, 1935

3 Claims. (Cl. 114—0.5)

This invention relates to a watercraft with friction reducing, for example cylindrical floats supporting the hull above the surface of the water and, the floats arranged in chains being capable of limited movement, preferably on the surface of the water so as to follow the movement of the water (waves).

The object of the invention is to obtain balancing and consequently a considerable increase in the travelling speed of a watercraft with the above stated features and to make this type of watercraft seaworthy whilst the pitching motion in rough weather is reduced as much as possible or even eliminated.

The invention consists in that the floats in a watercraft having the above mentioned features are threaded on stretched ropes to form float chains or are arranged in some other suitable manner on stretched ropes or yieldable links.

According to the invention, in the case where the float chains are supported at a number of points, the individual float chains are supported on the carrier frame of the hull along their entire length at points situated relatively far apart.

The means for supporting the float chains relatively to the carrier frame of the hull are, according to the invention, so constructed that they are to a limited extent elastic, yieldable or articulated yet afford a firm support.

The invention likewise consists in that the means for supporting the float chains relative to the carrier frame of the hull and, if desired, also the carrier frame, consist of lattice work in space with great compressive strength braced by metal wire and offering little resistance to the medium (water, air) to be cleaved.

The floats can with advantage be in the shape of a bottle or cone, an ellipsoid or a ball.

Several embodiments of the invention are illustrated by way of example in the accompanying drawing in which:—

Fig. 1 shows the watercraft in side elevation with ball-float-chains arranged in longitudinal direction under the carrier frame for the hull.

Fig. 2 shows on a larger scale a similar view of the carrier frame with a slightly modified arrangement of floats.

Fig. 3 is a cross section on line III—III of Fig. 2.

Fig. 4 is a perspective view of the carrier frame.

Fig. 5 shows in side elevation a carrier frame with bottle-shaped float-chains.

Figs. 6 and 7 show in plan view two different arrangements of float chains, without hull or carrier frame.

Fig. 8 is a side elevation of the carrier frame with the float chains arranged in the transverse direction of the craft.

Fig. 9 is a section on line IX—IX of Fig. 8.

The form of construction of the watercraft illustrated in Fig. 1 comprises a carrier frame 1, situated above the water level, and supporting a hull 2 of any suitable shape destined to accommodate passengers and loads equipped at intervals laterally or preferably underneath with floats 3 arranged and constructed in a special manner. If, as in the example illustrated, the watercraft is driving by one or more propellers 4 arranged above the water the hull 2 may be guttiform or stream-lined. The craft can be steered by an air rudder 5 or by a rudder mounted on the frame 1 below the surface of the water. In the case of drive by air-propeller, the hull 2 and/or the carrier frame 1 may be equipped with supporting planes or wings 6 or the like similar to those used on flying boats, so as to impart a certain buoyancy to the craft for reducing the friction in the water. These wings 6 must not, however, make the craft capable of flying, seeing that the invention relates to a real watercraft which can be steered by persons uninitiated in aviation.

The floats, which are generally designated by 3 in Fig. 1, may, according to the invention, be arranged and constructed in various ways; they are preferably of spherical, conical or bottle-shape and may be rigid hollow bodies or inflatable and wholly or partly elastic, so that they can be given a greater or smaller displacement volume according to the load to be carried.

The carrier frame situated between the floats and the hull is preferably composed of lattice work, consisting of stays of uniform length arranged diagonally and interconnected at their points of intersection, and over the ends of which a wire is tightly stretched by coiled springs 17, as also shown in Figs. 2 and 5 so that the frame thus assembled presents the least possible resistance to the medium (air and possibly water in the case of high seas) to be cleaved when the craft is travelling. Such lattice work sections formed of stays and stretched wire have a great compression strength, and as they, at the same time, offer but slight resistance to the medium, are also particularly suitable for the carrier frame. They are cheap to build and of comparatively light weight. A carrier frame 1 composed of such structures is illustrated in all the examples shown in the drawing and can be seen most clearly in Fig. 4.

In Figs. 2 and 3 spherical floats 10 are pro-

- vided which are threaded on ropes 11 in such a manner that they can rotate thereon. The ropes are yieldably stretched so that the floats 10 are capable of limited movement in all directions.
- 5 They can move both in vertical and also in horizontal direction and thus follow the movements of the waves to a limited extent. The floats 10 are arranged in parallel rows in longitudinal direction underneath the carrier frame 1, the rows 10 of chains being subdivided into sections 12 and 13. The individual float chain sections 12, 13 may be yieldable along their length at intervals by stays, should the length of the carrier frame so require. Such intermediate stays are 15 indicated in Fig. 1.

Fig. 5 shows a similar arrangement to Figs. 2 and 3, but the floats 14 are of bottle- or conical-shape.

Fig. 6 shows in plan view an arrangement of 20 the float rows in which the float chains converge at 15 at the bow of the carrier frame, instead of extending parallel along their entire length, whereas the rear chain sections are arranged in three parallel rows along their entire 25 length.

Fig. 7 is a plan view showing another arrangement of the float chains.

In Figs. 8 and 9 the rows of floats 16 are arranged transversely to the direction of travel. 30 The arrangement is otherwise similar to that illustrated in Figs. 2 and 3. The transverse arrangement presents the advantage that the water friction is reduced owing to the rotation of the floats. The ropes on which the floats are threaded should in this instance be so stretched that 35 the floats can follow the movements of the water surface to a limited extent.

I claim:—

1. A water craft for high speeds driven by propellers, comprising in combination a hull, short supporting planes on said hull, a frame supporting said hull said frame consisting of 5 pressure-resisting lattice work formed by interconnected diagonal stays and wires on the ends of said stays bracing said stays, ropes carried by said frame and yieldable relatively thereto, and floats rotatably mounted on said ropes and 10 capable of limited movement in all directions at a distance from said frame.

2. A water craft for high speeds driven by propellers, comprising in combination a hull, short supporting planes on said hull, a frame 15 supporting said hull said frame consisting of pressure-resisting lattice work formed by interconnected diagonal stays and wires on the ends of said stays bracing said stays, ropes elastically supported by said frame and divided in the 20 length of said frame and yieldable relatively thereto, and floats rotatably mounted on said ropes and capable of limited movement in all directions at a distance from said frame.

3. A water craft for high speeds driven by 25 propellers, comprising in combination a hull, short supporting planes on said hull, a frame supporting said hull said frame consisting of pressure-resisting lattice work formed by interconnected diagonal stays and wires on the ends 30 of said stays bracing said stays, ropes carried by said frame and yieldable relatively thereto, and floats in the form of rotation bodies rotatably mounted on said ropes and united to form 35 float chains capable of limited movement in all directions at a distance from said frame.

ALEXANDER HERMAN.
